UNITED STATES PATENT OFFICE.

CARL J. A. SJOBERG, OF BRIDGEPORT, CONNECTICUT, ASSIGNOR TO THE SMITH & EGGE MANUFACTURING COMPANY, OF SAME PLACE.

BUTTON-HOLE ATTACHMENT FOR SEWING-MACHINES.

SPECIFICATION forming part of Letters Patent No. 406,115, dated July 2, 1889.

Application filed March 12, 1887. Serial No. 230,621. (No model.)

To all whom it may concern:

Be it known that I, CARL J. A. SJOBERG, a citizen of the United States, residing at Bridgeport, in the county of Fairfield and State of Connecticut, have invented certain new and useful Improvements in Button-Hole Attachments; and I do hereby declare the following to be a full, clear, and exact description of the invention, such as will enable others skilled in the art to which it appertains to make and use the same.

My invention has for its object to simplify and cheapen the construction, and at the same time to greatly improve the operation of this class of devices.

With these ends in view I have devised the simple and novel construction of which the following description, in connection with the accompanying drawings, is a specification, numbers being used to indicate the several parts.

Figure 1 is a side elevation of the device complete and in operative position on a sewing-machine, a portion of the bed-plate and the head of the machine being shown to illustrate the mode of attachment thereto; Fig. 2, a plan view of the operative parts, the cap being in section, the position being at the beginning or ending of a button-hole; Fig. 3, a longitudinal section on the line $x-x$ in Fig. 2; Fig. 4, a plan view corresponding with Fig. 2, except that the parts are in position just after the first turn—that is, at the beginning of the last half of the button-hole; Fig. 5, a longitudinal section on the line $y-y$ in Fig. 4; Fig. 6, a front elevation of the attachment; and Fig. 7, a rear elevation thereof, the parts being in the same position as in Figs. 1, 2, and 3; Fig. 8, a plan view, the position of the parts being the same as in Fig. 2, except that the feeding mechanism is removed; Fig. 9, a similar view to Fig. 8, showing the parts in the same position as in Fig. 4; Fig. 10, a plan view corresponding with Figs. 2 and 8, the feeding mechanism and cloth-clamp being removed; Fig. 11, a similar view to Fig. 10, the position of the parts corresponding with Figs. 4 and 9; Fig. 12, an inverted plan view of the attachment complete; Fig. 13, a view of the cross-slide detached; Fig. 14, an inverted plan view of the ratchet for operating the cross-slide de-

tached; Fig. 15, a view of the cloth-clamp spring detached; Fig. 16, a longitudinal section of a portion of the cloth-clamp, showing the manner in which the length of the button-hole is adjusted; Fig. 17, a side elevation of the forward end of the cloth-clamp and the work-holder, showing the manner in which the clamp is attached in place; Fig. 18, a side elevation of the frame-work, all the operative parts being removed; Fig. 19, an elevation of the cutting mechanism detached; and Fig. 20 is a view of the cutter detached.

The frame-work of the attachment, consisting of bed-plate 1, side pieces 2, and standard 3, is struck out and formed from a single piece of metal.

4 denotes the oscillating work-carrier; 5, the feed-rack, which is made integral with or secured thereto; 6, the feed-pinion which engages said rack, and 7 the feed-wheel with which the feed-pinion is made integral or to which it is secured. It will be noticed (see Figs. 3, 4, and 5) that the edge of the feed-wheel is provided with two rows or sets of teeth which are inclined in opposite directions. The upper row I have designated by 8 and the lower row by 9.

10 denotes the reversing-plate, and 11 a screw-pin securing the feed-wheel thereto, all of which will presently be more fully explained.

12 denotes the feed-plate, which slides in ways 13 in the side pieces of the frame-work, lugs 14 being provided to engage these ways. 85 This plate is struck out and formed from a single piece of metal, and lugs 15 at the opposite ends of the plate are turned downward at right angles thereto, forming bearings which hold the plate securely in its operative position.

16 denotes the feed-pawls, which are placed one above the other, and are secured by a screw-pin 17 to the feed-plate. It will be seen in Fig. 7 that one of these pawls engages the upper row of teeth, the other the lower row. The ends of both pawls are provided with downwardly-turned lugs 18, which engage openings 19 in the feed-plate to limit the motion of the feed-pawls. A spring or pair of springs 20, engaging the backs of the feed-pawls, acts to force them both inward, so that

each is in position to engage its corresponding set of teeth in the feed-wheel at the proper time.

21 denotes the feed-slide, which is provided with rack-teeth 22, which are engaged by rack-teeth 23 on feed-lever 24.

25 is an operating-lever, which is provided with the ordinary slot 26 to engage the needle-bar of the machine. The operating-lever and 10 the feed-lever are both secured to the standard by a screw-pin 27. The upper end of the feed-lever is provided with a flange 28 and set-screws 29, the points of which bear against the operating-lever to limit the vibration 15 thereof, so as to adapt the attachment to different styles of machines.

30 is a plate made integral with or secured to the feed-slide, and which is provided with a pin or lug 31, engaging slot 32 in the feed- 20 plate, whereby motion is imparted to the latter.

33 denotes the cross-slide which operates the oscillating and shifting mechanism. This cross-slide moves in openings 33^a in one of 25 the side pieces of the standard, and is provided with an opening 34, said opening being provided on opposite sides with cam-surfaces 35. This cross-slide is operated by means of a cam 36 upon the under side of a ratchet 37. 30 This cam lies within opening or yoke 34, and is ordinarily made three-sided, as shown in the drawings, the cam and cam-surfaces 35 being so laid out relatively to each other that each actuation of the ratchet throws the cross- 35 slide to one extreme or the other of its movement. For instance, to move it toward the right, one of the points 38 of the cam 36 would engage the right cam-surface 35, as the plate lies in the machine, and one of the sides 39 of 40 cam 36 would be in contact with the left cam-surface 35. To move the slide toward the left, one of the points would be in contact with the left cam-surface and one of the sides in contact with the right cam-surface. Cam 45 36 is actuated by a pawl 40, carried by feed-slide 21.

41 denotes a spring acting to hold this pawl in engagement with the ratchet. The respective positions of this pawl in actuating 50 the ratchet are shown in Figs. 2 and 4 and in Figs. 8 and 9.

42 denotes an oscillating lever carrying a double pawl 43 at its forward end, the functions and operation of which will presently 55 be explained. This link is secured to the cross-slide by a pin 44, and its rear end is socketed in a recess 45 in the bed-plate of the attachment. The oscillatory motion of the work-carrier is imparted through the cross- 60 slide.

46 is a screw-pin which passes through a slot 47 in the work-carrier and engages hole 48 in the cross-slide. The reversing-plate 10 is provided at its rear end with a slot 49, 65 which engages a stump 50 upon a plate 51, adjustably secured to the bed-plate.

52 is a friction-spring secured to the bed-

plate and bearing on the reversing-plate to hold it in operative position.

53 is a slot in the reversing-plate engaged 70 by a pin 54, projecting upward from the bed-plate, whereby the plate is held in position and its oscillation limited. At the forward end of the reversing-plate are two sets of rack-teeth, (indicated, respectively, by 55 and 56,) 75 both sets of which incline toward the center, there being a smooth surface 62 between the two sets of teeth. Both sets are adapted to be engaged by the respective arms of double pawl 43. Upon the back of this pawl is a V- 80 shaped teat or projection 57.

58 is a spring upon the cross-slide, made V-shaped at its forward end, so as to engage the opposite sides of the V-shaped teat or projection, thus acting to hold either end of the 85 pawl in engagement with its respective set of rack-teeth upon the end of the reversing-plate.

It may be here observed that the pivotal point of the work-carrier 4 (or that point on which it swings laterally to enable the over-edge or button-hole stitches to be produced) is coincident with the feed-pinion 6, said work-carrier having a pivotal connection with the cross-slide 33, which imparts the lateral oscillating movements to said work-carrier necessary for the production of the overedge stitching, the bearing shoulders or disks 66 and 67, (hereinafter referred to,) which hold the pinion 6 and rack 5 in engagement with each other, being concentric with said pinion. 90 100

As the pinion 6 and feed-wheel 7 are mounted on the pivoted reversing-plate, it is obvious that they will be moved laterally with the said plate when the latter is swung one way or the other, such lateral movements of the feed-wheel and pinion and of the shoulders or disks 66 and 67, rigidly connected to and thus movable therewith, serving to give a sufficient lateral throw to the forward or work-clamp end of the said feed-plate to form the barring-stitches at the ends of the button-holes and to bring the work into proper position beneath the needle of the machine to work the second side of a button-hole after the first side thereof has been worked, or to bring the work-clamp 115 into its initial position for the working of a new button-hole after the second side of a button-hole has been worked, such lateral movement being known as the "shipper" movement, in contradistinction to the vibrat- 120 ing or "overstitch" movements.

The stump or projection 50, which extends into the slot 49 of the reversing-plate, serves as a fulcrum for said plate, or as a pivotal point on which said plate will swing when operated 125 by the pawl 43 in effecting the shipper or ship-over movements of the work-carrier. By loosening the screw by which the plate 51 is secured to the bed-plate 1 the said plate 51 may be moved to adjust the fulcrum projection 50 in or out of the slot 49, and by thus changing the position of the said fulcrum the shipper movement may be regulated to vary 130 or adjust the distance apart of the lines of

stitches forming the worked button-hole, as may be required.

The operation of the parts already described is as follows: Each upward or downward movement of the needle-bar of the machine, acting through the operating-lever, imparts a movement in one direction or the other to feed-lever 24, which in turn moves the feed-slide through the engagement of rack-teeth 23 on the feed-lever with rack-teeth 22 on the feed-slide. As already stated, feed-plate 12 is caused to reciprocate through the engagement of pin 31 with slot 32 in the plate, so that each reciprocation of the feed-lever causes a reciprocation of the feed-slide and the feed-plate. At the commencement of each button-hole the parts are in the position shown in Figs. 2, 8, and 10. The reversing-plate is swung toward the right, as in Fig. 10—that is, looking from the front of the machine, as in Fig. 6. This of course swings the feed-wheel toward the right and brings the right feed-pawl in engagement with its corresponding set of teeth upon the feed-wheel, the under set, as shown in the drawings—that is, the set the action of which is to move the work-carrier forward, as in Fig. 2. It will of course be understood that the feed-plate is recessed out to afford ample room for the movement of the feed-wheel, the recess being indicated by 59, (see dotted lines in Figs. 2 and 4,) the other dotted line in these figures denoting openings 60 through the cap. (Shown also in Figs. 3 and 5.) This cap is denoted by 61, and is secured in any suitable manner to the side pieces. As the feed-plate reciprocates in its bearings, it follows that each forward movement thereof will cause the right feed-pawl to impart a forward movement to the feed-wheel. When the plate moves backward, the pawl slips over the teeth in the usual manner, re-engaging the teeth again at the end of the backward movement, ready to carry the wheel forward again with the next forward movement of the feed-plate. As the feed-pinion and feed-wheel move together, it follows that the work-carrier must move forward through the engagement of the pinion with feed-rack 5 upon the work-carrier. The oscillation of the work-carrier, whereby the cross-stitching of the button-hole is produced, is accomplished by the movement of the cross-slide, to which it is pivoted, as already explained. Each forward movement of the feed-slide causes pawl 40 to engage ratchet 37 and impart a movement thereto, which, by means of cam 36 and cam-surfaces 35 upon the cross-slide, imparts to said slide a movement in one direction or the other. While the work-carrier is moving forward the right point of double pawl 43 rests upon the smooth surface 62 at the end of the reversing-plate between the two sets of rack-teeth 55 and 56, as in Fig. 10, said pawl and the reversing-plate being inoperative during this forward movement. The forward movement continues until the end of the button-hole

is reached, at which instant stump 63 upon the under side of the work-carrier engages lug 64 on the double pawl 43, tripping said pawl and bringing the left point thereof into engagement with the left set of rack-teeth at the rear end of the reversing-plate, (denoted by 56.) It will be seen that spring 58, which engages seat 57 on the double pawl, 75 acts to hold it in either position into which it may be thrown, and that friction-spring 52 acts to hold the reversing-plate in position, so that at each movement of the cross-slide toward the right the left point of pawl 43 will 80 slip backward over one of the rack-teeth in set 56. The movement of the cross-slide toward the left of course carries lever 42 and double pawl 43 in that direction, so that through the movements of the cross-slide, link, 85 and pawl the reversing-plate is quickly moved from the position shown in Fig. 10 to that shown in Fig. 11, which completes that end of the button-hole. As soon as the reversing-plate and the left point of pawl 43 have 90 reached the position shown in Fig. 11 they both become inoperative again. While these movements of the reversing-plate have been taking place the feed-wheel has of course been inoperative, as neither feed-pawl has 95 been in engagement therewith. As soon as the movement of the reversing-plate is completed and the left point of the double pawl has passed over all the teeth in set 56 and is resting upon the smooth surface 62, as in Fig. 100 11, the feed-wheel will have been moved to a position that will place the left feed-pawl in engagement with the other row of teeth—in the present instance the upper row—in the feed-wheel, as in Fig. 4. This reverses the 105 movement of the feed-wheel, and consequently of the feed-pinion, so that the work-carrier begins to travel backward to complete the other side of the button-hole. The movement down the other side of the button-hole continues until adjustable stump 65 upon the under side of the work-carrier comes in contact with lug 64 on the double pawl 43, which trips it again and brings the right point thereof in engagement with the set of teeth 115 55 at the forward end of the reversing-plate. The action in reversing is the same as before until the right point of pawl 43 has acted upon each tooth in set 55 in turn, from the outer one inward, which completes the other 120 end of the button-hole, the parts being again in the position shown in Figs. 2, 8, and 10. It is of course preferable to run a few stitches over the point at which the stitching commenced in order to fasten the ends securely. 125

As this attachment is applicable to all the different sewing-machines now upon the market, I have of course omitted all description and illustration of stitching mechanism, which may be of any preferred make.

66 and 67 denote shoulders upon the under side of the feed-wheel, the lower one resting in slot 68 at the rear end of the work-carrier over the edge of the rack and the upper one

resting in a recess 59 in the feed-plate. These shoulders serve as bearings and hold the parts firmly in position in use.

It will be noticed in Figs. 2 and 4 that a gage 69 is provided upon the top of the feed-wheel, and in Figs. 4 and 8 that a gage 70 is provided upon the top of the work-carrier by the side of slot 71. Stump 65 upon the under side of the work-carrier is made adjustable by means of set-screw 72, which passes through slot 71 and engages said stump. The adjustment of this stump determines the point at which the second crossing or barring of the button-hole takes place—that is, the point at which the second movement of the reversing-plate takes place.

The attachment illustrated in the drawings is capable of producing an inch-and-a-quarter button-hole for its larger size. If a button-hole of this size is desired, set-screw 72 is loosened and the stump pushed to the extreme forward end of slot 71. If a half or three-quarter inch button-hole is desired, the stump is set to the proper position, as indicated by gage 70, in order to make the second crossing, barring, or turn at the proper time. The position of the work-carrier and cloth-clamp when commencing to work the button-hole is determined by the adjustment of the feed-wheel, which is provided with a finger-knob 73, for convenience in operation, this finger-knob being always within reach through the opening in the cap. (See Fig. 3.)

74 (see Fig. 5) denotes a projection or point in the edge of opening 60 through the cap, which is the mark used to determine the position in which the feed-wheel is to be set when a button-hole of a certain length is to be made, as determined by the position of adjustment of the adjustable stump 65.

Supposing it is desired to make a half-inch button-hole, the parts being of course in the position shown in Figs. 2, 8, and 10, the feed-wheel is moved forward until the point marked one-half on gage 69 is brought in line with projection 74, when the machine may be started.

As stated above, while either point of double pawl 43 is acting upon the reversing-plate, both feed-pawls are out of engagement with the feed-wheel; consequently no forward movement of the work-carrier takes place until movement of the reversing-plate is completed, so as to bring the feed-wheel into position to be engaged by the other feed-pawl.

When the attachment is not in place upon the machine, the work-carrier may be readily moved backward or forward by rotation of the feed-wheel by hand. In order, however, to prevent the work-carrier from moving far enough in either direction to allow either of the stumps 63 or 65 to forcibly engage lug 64 on the double pawl, and thus prevent the reversing mechanism from acting, I have provided a stop 75, preferably made integral with friction-spring 52, which engages shoulders 76 in the edge of the work-

carrier, thereby limiting its movement in both directions and avoiding the possibility of either stump moving far enough to anything more than trip the double pawl, thus preventing injury to the reversing mechanism.

77 denotes the needle-hole in the bed-plate.

The forward end of the work-carrier is of ordinary construction, and is provided with the usual opening 78.

79 is a cloth-clamp having flanges 80, which extend down into this opening, thus holding the work firmly, and rearwardly-extending arms 81, which are joined by a cross-piece 82.

83 denotes lugs which project downward from the cross-piece, and are provided with notches 84, adapted to engage projections 85 on the edge of the work-carrier.

86 denotes a standard projecting upward from the work-carrier between arms 81 of the cloth-clamp.

87 denotes a clamping-lever pivoted to the standard. The head of this lever has two straight faces, one of which is continuous with the handle and the other at right angles thereto, the face in line with the handle being at a greater distance than the other from the pivotal point, so that when the handle is turned downward the cloth-clamp is pressed down upon the work-carrier, flanges 80 passing into opening 78. When the other face of the clamping-lever is in contact with the cloth-clamp—that is, when the handle is in the raised position, as in Fig. 17—the cloth-clamp is raised above the work-carrier by the action of a spring 88 lying under said carrier. Any style of spring may of course be used for this purpose, although I preferably make a special spring having a plate 89, with a slot 90, adapted to engage the standard. The spring, being simply slipped over the standard, is held firmly in position at all times without the use of rivets or screws.

In order to provide simple and convenient means for cutting the button-hole after it has been stitched, I have devised a cutting mechanism adapted to be used in connection with the needle bar, cap, and standard 86, which I will now describe.

91 (see Figs. 2 and 19) denotes a plate substantially a right angle in form, which is provided with a slot 92, adapted to engage standard 86 above clamping-lever 87, when it is in the locked position, with needle-holes 93, to adapt it for different button-holes, different machines, &c., and a rearwardly-extending shank 94, which is bent downward and rests in a loop 95, formed integral with the cap, as clearly shown in Figs. 6 and 7.

96 (see Figs. 19 and 20) denotes a cutter-blade, the edge of which is made of just the required length to cut the special length of button-hole that is being stitched.

Plate 91 is provided with a downwardly-projecting flange 97, the ends of which are curved around, forming sockets which embrace the cutter. The cutter is firmly secured in place by a set-screw 98, which passes

through slot 99 in the cutter and engages flange 97.

The operation is as follows: The cutter has to be placed in position for each button-hole; 5 but as there are no adjustments it takes but an instant to do so. The shank simply has to be slipped into loop 95 and the plate passed over the standard which engages slot 92. To cut the button-hole, the fly-wheel of the machine is moved by hand, which of course 10 brings the needle-bar down and causes the end thereof denoted by 100 to engage the top of plate 91 on opposite sides of the special hole through which the needle passes. This of course forces the cutter down and cuts the 15 button-hole.

101 denotes the slot in the bed-plate through which the cutter passes in cutting a button-hole. It should be noticed (see Figs. 11 and 20 12) that this slot is placed at one side of the needle-hole in the bed-plate, and is wholly independent thereof. The slot is made long enough to accommodate any length of button-hole, and no changes in the attachment are 25 required in cutting different lengths. The cutting is of course done when the needle-bar is down, at which instant the work-carrier is oscillated toward the left, as seen in Fig. 2, so that the cutter-blade enters said slot without 30 interference with any part of the machine or attachment.

In use the attachment is secured directly to the rear slide 102 of the machine.

103 (see inverted plan view, Fig. 12) denotes 35 screws which pass through the slide from beneath and engage the bed-plate 1 of the attachment.

104 denotes a longitudinal slot in the slide which curves out to the edge thereof, forming 40 a strip 106.

105 denotes a set-screw which passes through the bed-plate of the attachment, the point of which engages the outer side of slot 104, acting 45 to spring strip 106 outward against the slide-groove (not shown) in the bed-plate of the machine, thus locking the attachment firmly in place.

The operation of the attachment is briefly as follows: The rear slide of the machine is 50 taken out and the attachment secured thereto. The slide is then pushed into place and locked there by set-screw 105. The feed-wheel and adjustable stump 65 upon the under side of the work-carrier are adjusted to 55 the proper length of button-hole, the work placed in position under the cloth-clamp and secured there by the clamping-lever. The operation of stitching the opposite sides of the button-hole and barring the two ends and 60 the movements of the parts in accomplishing this result have been so clearly described as not to require repetition. When a button-hole is completed, the cutter, without disturbing any of the parts, by a single movement of 65 the fly-wheel, is caused to cut the button-hole. The cutter is then removed, the cloth-clamp

lifted, and the working of another button-hole proceeded with as before.

Having thus described my invention, I claim—

1. In a button-hole-sewing attachment for sewing-machines, the combination, with a pivoted work-carrier provided with a single rack, and means for vibrating said carrier to produce the overedge stitch, of a laterally-shifting plate, a feed-wheel and pinion journaled within and carried by said plate, and means controlled by the work-carrier and operated by the primary oscillating lever for shifting said plate and carrier when the latter has 75 reached the respective limits of its forward and backward movements, whereby the barring is effected and the opposite rows of overedge stitches are sewed, substantially as set forth. 80

2. In a button-hole attachment, the combination, with a pivoted work-carrier provided with a rack, and means for vibrating said work-carrier to produce overedge stitches, of a pinion and feed-wheel for feeding said work-carrier lengthwise, operating mechanism for said feed-wheel, a reversing-plate by which 90 said pinion and feed-wheel are carried, and automatically-operating appliances for moving said reversing-plate laterally when the 95 end of a button-hole is reached to effect the shipper movements of the said work-carrier.

3. In a button-hole attachment, the combination, with a work-carrier having a rack, of a pinion engaging said rack, a feed-wheel 100 connected with said pinion and having reverse sets of teeth, a feed-plate having alternately-operating pawls to actuate said feed-wheel, a feed-slide to operate said feed-plate, a feed-lever engaging said feed-slide, and an operating-lever having an adjustable connection 105 with said feed-lever.

4. In a button-hole attachment, the combination, with a work-carrier having a rack, of a pinion engaging said rack, a feed-wheel connected with said pinion and having reverse sets of teeth, a feed-plate having alternately-operating pawls to actuate said feed-wheel, a feed-slide to operate said feed-plate, a feed-lever engaging said feed-slide and provided 110 with adjusting or set screws, and an operating-lever for the said feed-lever.

5. In a button-hole attachment, the combination, with a work-carrier provided with a rack and with stumps or projections, a pinion for engaging said rack, and means for intermittently rotating said pinion in opposite directions, of a reversing-plate on which the said pinion is mounted and which is provided with separated sets of reversely-arranged 120 teeth, a double-pointed reversible pawl in position to be engaged by said stumps or projections, a moving part, as lever 42, to which the said pawl is pivoted, and means for actuating said moving part to operate said pawl. 125

6. In a button-hole attachment, the combination, with a work-carrier provided with a

rack and with stumps or projections 63 65, a pinion engaging said rack, and means for operating said pinion, of a reversing-plate by which the said pinion is carried, and which is provided with two separate and reversely-arranged sets of teeth, a double-pointed reversible pawl 43 in position to be engaged by said stumps or projections, a lever 42, by which said pawl is carried, the cross-slide 33, connected with said lever, and means for reciprocating said cross-slide.

7. In a button-hole attachment, the combination, with a work-carrier provided with a rack and with stumps or projections 63 65, a pinion engaging said rack, and means for operating said pinion, of the pivoted reversing-plate 10, by which the said pinion is carried, and which is provided with the separated sets of teeth 55 56, the lever 42, the cross-slide 33, connected with said lever, means for operating said cross-slide, the reversible double-pointed pawl 42, carried by said lever and having the lug 64 and the V-shaped projection 57, and the spring 58, to engage the opposite sides of said projection.

8. In a button-hole attachment, the combination, with a work-carrier provided with a rack and with the stumps or projections 63 65, one of which is adjustable, of a pinion engaging said rack, means for intermittently rotating said pinion in opposite directions, a pivoted reversing-plate by which said pinion is carried, and which is provided with reverse sets of ratchet-teeth, a reversible double-pointed pawl in position to be engaged by said stumps or projections, the lever 42, by which said pawl is carried, and means for operating said lever.

9. In a button-hole attachment, the combination, with a work-carrier provided with a rack and stumps or projections 63 65, of a pinion engaging said rack, means for operating said pinion, the pivoted reversing-plate 10, having two reverse sets of ratchet-teeth 45 and slot 53, the bed-plate having the pin 54, a reversible double-pointed pawl in position to be engaged by said stumps or projections, a movable part by which said pawl is carried, and means for operating said movable part.

50 10. In a button-hole attachment, the combination, with a work-carrier 4, having the rack 5, of the pinion 6, the feed-wheel 7, having the reverse sets of teeth 8 9, the pivoted reversing-plate 10, by which the said pinion and feed-wheel are carried, means for shifting said reversing-plate laterally, the feed-plate 55 21, having the slot 32, the spring-pressed pawls 16, carried by said plate, the feed-slide 21, having teeth 22 and pin 31, the feed-lever 60 having teeth 23, and the operating-lever 25.

11. In a button-hole attachment, the combination, with a work-carrier 4, having the rack 5 and the stumps or projections 63 65, of the pinion 6, the feed-wheel 7, having reverse sets of teeth 8 9, the pivoted reversing-plate having the reverse sets of teeth 55 56,

separated from each other, the feed-plate 12, having the slot 32 and the spring-pressed pawls 16, the feed-slide 21, having the pin 31, means for reciprocating said slide, the double-pointed reversible pawl 43, the lever 42, by which said pawl is carried, the cross-slide 33, connected with said lever, and means for reciprocating said cross-slide.

12. In a button-hole attachment, the combination, with a work-carrier provided with a rack and with stumps or projections, a pinion engaging said rack, and means for rotating said pinion in opposite directions, of a reversing-plate by which said pinion is carried, and which is provided with two sets of teeth, a reversible pawl in position to be engaged by said stumps or projections, a moving part, as lever 42, by which said pawl is carried, means for operating said moving part, and spring 52, pressing against said reversing-plate and serving to hold it in the different positions to which it may be moved by said pawl.

13. In a button-hole attachment, the combination, with the work-carrier 4, having the rack 5 and the stumps or projections 63 65, of the pinion 6, the feed-wheel 7, having reverse sets of teeth 8 9, the feed-plate 12, having slot 32 and pawls 16, the feed-slide 21, having pin 31 and the pawl 40, means for reciprocating said feed-slide, the reversing-plate 10, having sets of teeth 55 56, the spring 52, the cross-slide 33, having a yoke or opening, the cam 36, and the ratchet-wheel 37, with which the said cam rotates.

14. The combination, with a button-hole attachment, of a cutting-blade of proper length to cut an entire button-hole at a single stroke, a removable cutter-holding plate by which the said blade is carried, and supports on said attachment for removably holding said plate in place on the attachment, with the cutting-blade in cutting position beneath the needle-bar of the sewing-machine.

15. The combination, with a button-hole attachment, a cutter-holding plate 91, and means for removably supporting the same on the attachment, said plate being provided with a cutter-retaining flange 97, of the blade 115 or cutter 96, having the slot 99, and the set-screw 98, for detachably securing said blade to said flange.

16. In a button-hole attachment, the combination, with the bed-plate 1, having the slot 101, of the cap having the loop or upturned projection 95, the work-carrier having the standard 86, and the removable cutter consisting of the plate 91, having an opening or slot to receive said standard, the arm or shank 125 94, to engage said loop or projection, and the needle-holes 93, and a cutting-blade or cutter proper 96.

17. In a button-hole attachment, the combination, with the work-carrier, its rack and pinion, and operating mechanism for the latter, of the pivoted reversing-plate by which

said pinion is carried, an adjustable fulerum for said plate, and means for swinging said plate laterally on its fulerum when the end of a button-hole has been reached.

5 18. In a button-hole attachment, the combination, with a work-carrier provided with a rack, of a pinion engaging said rack, means for operating said pinion, a pivoted reversing-plate by which said pinion is carried, and 10 which is provided with the slot 49, the adjustable plate 51, having the stump or projection 50 extending into the said slot 49 and serving as a fulcrum for said reversing-plate, and means for swinging the said reversing- 15 plate laterally on its fulcrum stump or projection when the end of a button-hole has been reached.

19. In a button-hole attachment, the combination, with the work-carrier having a rack, 20 of a pinion engaging said rack, a feed-wheel connected with said pinion and having reverse sets of teeth, operating mechanism for said feed-wheel, a reversing-plate by which said pinion and feed-wheel are carried, means 25 for operating said reversing-plate, a feed-plate provided with openings 19, and two spring-pressed pawls having lugs extending into said openings, and thereby having their movements limited.

20. In a button-hole attachment, the combination, with a gage 70 and a work-carrier having a rack, of a pinion engaging said rack, a feed-wheel connected with said pinion and having a gage 69, mechanism for operating said feed-wheel and for reversing the direction of its rotation, and the cap or housing having an opening 60, and a point 74, to serve 30 as an indicator in connection with the said gage 69.

21. In a button-hole attachment, the combination, with a work-carrier provided with a rack and with the reversing stumps or projections 63 65, and having also a slot 71, in which stump 65 is adjustable, and a gage 70, adjacent to said slot, of a pinion engaging said 40 rack, a feed-wheel connected with said pinion and provided with a gage 69, a reversing-plate by which said feed-wheel and pinion are carried, means for operating said feed-wheel and reversing-plate, and a cap having 45 a point 74, to serve as an indicator for the said feeding-wheel gage.

In testimony whereof I affix my signature in presence of two witnesses.

CARL J. A. SJOBERG.
